(57) **CLAIM**

The ornamental design for a laser beam reflector, as shown and described.

DESCRIPTION

FIG. 1 is a front view of a laser beam reflector of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top plan and left side perspective view thereof;

FIG. 8 is a front, bottom plan and left side perspective view thereof;

FIG. 9 is a cross-sectional view along the line 9-9 in FIG. 3; FIG. 10 is a cross-sectional view along the line 10-10 in FIG. 3; and,

FIG. 11 is a front, top plan and left side perspective view thereof in the state of use.

The features shown in broken lines depict environmental subject matter only and form no part of the claimed design.
